CONTROL VALVE FOR WATER BELLS

Joseph H. Mosel, Columbus, Ohio, assignor to The
Jaeger Machine Company, Columbus, Ohio, a
corporation of Ohio

Application December 28, 1939, Serial No. 311,386

6 Claims. (Cl. 251—119)

My invention relates to a control valve for water bells. It has to do, more particularly, with a control valve adapted to be associated with a water supply bell of the type disposed in the drum of a concrete mixer, such as a truck mixer. It is applicable to the water bells disclosed in Figures 1 to 3 of the copending application of Gebhard Jaeger, Serial No. 201,250, filed April 11, 1938. However, it may be employed with other types of water bells.

One of the objects of my invention is to provide a control valve for water bells of the type indicated which is of such a nature that it will permit efficient discharge of the water into the loaded mixing drum without danger of the material in the drum entering the bell or rendering the valve inoperative.

Another object of my invention is to provide a valve of the type indicated which is of such a nature that it will open readily and efficiently when water is supplied to the water bell and will close and seal itself when the flow of water thereto is interrupted.

Another object of my invention is to provide a valve of the type indicated which is of such a nature that the parts thereof will not be worn readily by the concrete in the drum so that the valve will leak after being used for a short period.

Another object of my invention is to provide a valve of the type indicated in the preceding paragraph which is of such a nature that if any part does wear to an undesirable extent after long usage, it may be removed readily and replaced.

The preferred embodiment of my invention is illustrated in the accompanying drawing wherein similar characters of reference designate corresponding parts and wherein:

Figure 1 is a side elevation, partly broken away, illustrating a truck mixer with water bells disposed therein to which my control valve may be applied.

Figure 2 is a sectional view taken through the casting which form the water bells and showing my valve applied to each of the bells.

Figure 3 is a view looking into one of the bells, parts being broken away for clearance.

Figure 4 is a section taken through one of the bells illustrating how my control valve functions.

Figure 5 is a perspective view showing the parts of my control valve in spaced relationship.

With reference to the drawing, in Figure 1 I have shown a truck mixer embodying a rotatable mixing drum 1. Within the mixing drum a water pipe 2 is axially disposed and carries a casting 3 which has water bells 4 and 5 formed thereon as

described in the copending application S. N. 201,250. My control valve is adapted to be applied to each of the water bells 4 and 5. However, it is to be understood that it may be applied to various other types of water bells.

According to the present invention each of the water bells is provided with a frusto-conical or bell shaped portion 6 at its outer end. At the inner end of portion 6 a supporting spider 7 is formed integral with the bell casting. This spider 10 7 has a hub portion 8 having a threaded opening formed therein.

The valve itself is formed by an inner disk 9 of steel which is of concave form. This disk has a chamfered edge 10 which will contact with the inner surface of the portion 6. The steel disk 9 has secured to its outer surface a gum rubber disk 11 which will also be of concave form and will lie in contact with the steel disk throughout its area. This rubber disk is also provided with a 20 chamfered edge 12 which contacts the inner surface of portion 6 and produces a seal at this point.

The disks 9 and 11 are secured together by a plurality of rivets 13 disposed around the center thereof and closely adjacent to same. These two 25 disks are provided with aligning openings 14 which are disposed at circumferentially spaced points and which are spaced a substantial distance from the peripheral edges of the disks. The disks 9 and 11 are secured together as a unit 30 by the rivets 13. To prevent the rivets from pulling through the rubber disk 11 a small metal disk 15 is provided which bears against the outer surface of rubber disk 11 adjacent the center thereof.

A second gum rubber disk 16 is provided which is adapted to bear against the outer surface of the rubber disk 11. This disk is flat before being mounted in the valve. It is held in position by means of a small metal disk or a washer 17 which bears against the center portion only thereof. The washer 17 is held in position by a bolt 18 which passes through aligning centrally disposed openings formed in members 17, 16, 11 and 9 and which is threaded into the hub 8 of the supporting spider 7. Thus all of 35 40 these members will be tightly clamped together.

A lock washer 19 is provided for normally preventing loosening of the bolt. The disk 16 is of such diameter that its peripheral edge will not contact with the inner surface of portion 6 of the 45 bell. Although the disk is flat before being positioned in the bell, it will assume the curvature of the disk 11 when it is mounted in the bell and will seat on the disk 11 substantially throughout its area.

It will be apparent that this valve is normally closed. The disk 16 will normally be seated on the disk 11 and will effectively seal the openings 14. The edge 12 of the disk 11 will seat against the inner surface of the bell and will produce an effective seal at this point. The edge 10 of the disk 9 will also seat against the inner surface of the bell and form a seal.

When water is supplied to the bell under pressure, it will pass out through the openings 14 forcing the rubber disk 16 outwardly and will be sprayed outwardly by the portion 6 of the bell, as indicated in Figure 4. The water will not pass around the edges of the disks 9 and 11 since seals are formed at these points. As soon as the water pressure is eliminated, the disk 16 will again seat on the disk 11. This will prevent any concrete from entering the valve.

The pressure of the concrete on the disk 16 will merely enhance the sealing action. Furthermore, if any particles do work under the edges of the disk 16, the seal will not be affected because there is a rubber to rubber contact of the disks 11 and 16. Furthermore, because of this rubber to rubber contact there will be substantially no wear produced by any particles entering between these members. If it is desired to remove any parts, this may be readily done merely by removing the bolt 18.

With this combination an improved sealing of the water bell is obtained. The holes 14 are covered by the outer rubber disk 16 even though the edge of this outer rubber disk is worn or wrinkled. This combination, in effect, offers a double seal. First, the perimeter inside the bell is sealed by the combination rubber and metal disk 9 and 11, having the holes 14. Secondly, the outer rubber disk 16 seals the perimeter, and, even if there is failure at this point, it still further seals against the holes 14. Thus, even if the outer rubber disk becomes wrinkled badly or worn badly, or a stone catches under the edge thereof, the holes 14 are still sealed by this outer rubber disk.

It will be apparent from the above description that I have provided a valve for water bells having many advantages. The valves will open readily and efficiently when water is supplied to the bell and will close and seal itself when the flow of water thereto is interrupted. When closed there will be no danger of the concrete entering the bell or rendering the valve inoperative.

Various other advantages will be apparent from the preceding description, the drawing, and the following claims.

Having thus described my invention, what I claim is:

1. In combination, a water bell, a supporting spider disposed within said bell and having a centrally disposed hub, a metal disk of concave form disposed within said bell and bearing against said hub, said metal disk having a chamfered edge in contact with the inner surface of said bell, a rubber disk of similar concave form bearing against the outer surface of said metal disk and being riveted thereto adjacent the center thereof, said rubber disk also having a chamfered edge bearing against the inner surface of said bell, said metal disk and said rubber disk having aligning openings disposed at circumferentially spaced intervals but spaced from the peripheral edge thereof, a flat rubber disk held in contacting relationship with the outer surface of said first-named rubber disk by a washer bearing against the central portion only thereof, and

a bolt passing through aligning centrally disposed openings formed in said washer and all of said disks and being threaded into an aligning opening formed in said hub, said last-named rubber disk being of such diameter that it will not contact with the inner surface of said bell.

2. In combination, a water bell, a support within the bell, a metal disk of concave form disposed within said bell, said metal disk having a chamfered edge in contact with the inner surface of said bell, a rubber disk of similar concave form bearing against the outer surface of said metal disk and being secured thereto adjacent the center thereof, said rubber disk also having a chamfered edge bearing against the inner surface of said bell, said metal disk and said rubber disk having aligning openings disposed at circumferentially spaced intervals but spaced from the peripheral edge thereof, a flat rubber disk held in contacting relationship with the outer surface of said first-named rubber disk, and a bolt passing through aligning centrally disposed openings formed in all of said disks and being threaded into an aligning opening formed in said support, said bolt bearing against the central portion of said last-named disk, said last-named rubber disk being of such diameter that it will not contact with the inner surface of said bell.

3. In combination, a water bell for a concrete mixer or the like, a support within the bell, a metal disk of concave form disposed within said bell, a rubber disk of similar concave form bearing against the outer surface of said metal disk and being secured thereto, said rubber disk and said metal disk having their edges bearing against the inner surface of said bell, said metal disk and said rubber disk having aligning openings formed therein at points spaced from the edges thereof, a rubber disk held in contacting relationship with the outer surface of said first-named rubber disk, and a member passing through aligning centrally disposed openings formed in all of said disks and said support for securing all of said members in cooperative relationship, said second rubber disk being flexible so that it will be moved outwardly away from said first-named rubber disk by pressure exerted through said openings.

4. In a combination, a water bell for a concrete mixer or the like, a metal disk of concave form disposed within said bell, a rubber disk of similar concave form bearing against the outer surface of said metal disk, said rubber disk and said metal disk having their edges in contact with the inner surface of said bell, said metal disk and said rubber disk having aligning openings formed therein, and a second rubber disk held in contacting relationship with the outer surface of said first-named rubber disk, and means for holding all of said members in cooperative relationship, said second rubber disk being flexible so that it will be moved outwardly away from said first-named rubber disk by pressure exerted through said openings.

5. In combination, a water bell for a concrete mixer or the like, a metal disk of concave form disposed within said bell, a rubber disk of similar concave form bearing against the outer surface of said metal disk, said rubber disk having its edge in contact with the inner surface of said bell, said metal disk and said rubber disk having aligning openings formed therein, and a second rubber disk held in contacting relationship with the outer surface of said first-named rubber disk, said second rubber disk being flexible so that it

will be moved outwardly away from said first-named rubber disk by pressure exerted through said openings.

- 5 6. In combination, a water bell for a concrete mixer or the like, a metal disk disposed within said bell, a rubber disk bearing against the outer surface of said metal disk, said metal disk and said rubber disk having their edges in contact with the inner surface of said bell, said metal

disk and rubber disk having aligning openings formed therein, and a second rubber disk held in contacting relationship with the outer surface of said first-named rubber disk, said second rubber disk being flexible so that it will be moved outwardly away from said first-named rubber disk by pressure exerted through said openings.
